ELECTRIC IRON

Ernest Brauner, St. Louis, and Maurice J. Denning, St. Charles, Mo., assignors to The Emerson Electric Manufacturing Company, St. Louis, Mo., a corporation of Missouri

Application December 6, 1945, Serial No. 633,137

11 Claims. (Cl. 38—89)

1

The present invention relates to an electric iron.

It is an object of the invention to provide an electric iron which has complete protection of the hand of the operator from being burned by heat in the top section of the iron. It is a further object to provide an iron which has a streamlined construction, and hence a relatively low handle, without any danger of burning of the hand of the operator by its proximity to the hot parts of the iron.

More particularly, it is an object of the invention to provide an electric iron having a sole plate cover and separate laminations between the cover and the handle, one of which provides an air space and the other of which is of heat insulating material. It is a further object of the invention to provide an iron of the foregoing type in which a thermostatic heat adjustment is arranged for convenient operation by the finger of the operator of the iron and which is suitably heat protected to prevent the burning of the operator's hand upon the movement of the adjusting means. A further object is to provide the adjusting means in connection with a heat insulating plate covering the top of the base of the iron and separate from the handle proper that, nevertheless, is disposed conveniently at the front of the handle.

A further object of the invention is the provision of a novel control of the thermostatic means, including a novel arrangement and disposition of a thermostatic switch.

Further objects include the arrangement of the parts for quick assembly and disassembly.

Additional objects will appear in the description to follow, wherein:

Fig. 1 is a plan view of the iron;

Fig. 2 is a side elevation, partly broken away;

Fig. 3 is a rear elevation;

Fig. 4 is a horizontal section at the front of the iron on the line 4—4 of Fig. 2;

Fig. 5 is a substantially horizontal section beneath the insulating plate immediately below the handle, taken on the line 5—5 of Fig. 2;

Fig. 6 is a section of the toe of the handle, showing part of the handle locking means, taken on a medial line from front to rear of the handle;

Fig. 7 is a horizontal section of the forward part of the iron, taken through the shroud on the line 7—7 of Fig. 2;

Fig. 8 is a vertical section through the forward part of the iron, taken approximately on the line 8—8 of Fig. 2;

Fig. 9 is a side elevation of the thermostatic switch;

Fig. 10 is a vertical section, taken on the line 10—10 of Fig. 9, showing the thermostat adjusting means;

Fig. 11 is a vertical section through the switch blades, taken on the line 11—11 of Fig. 9;

Fig. 12 is a plan view of the base of the iron with the cover removed;

2

Fig. 13 is a side elevation of the base of the iron with the cover removed;

Fig. 14 is a rear elevation of Fig. 13;

Fig. 15 is a section on the line 15—15 of Fig. 12, showing the power line terminals;

Fig. 16 is a section of the rear of the handle on a medial line from front to rear thereof; and

Fig. 17 is a bottom view of the rear of the handle, as shown in Fig. 16.

10 The iron comprises a base or sole plate 20, as generally appears in Figs. 12—14. This section has a lower part 21 comprising the sole proper of the iron. The sole plate 20 includes the heating element and the thermostatic control, as will appear, along with necessary electrical connections. Above the sole plate and covering the top parts thereof is a cover or shroud 22. This cover has a more or less flat upper surface that inclines downwardly from front to rear of the iron. 15 Above it is located a hollow metal plate 23, to be described in greater detail. Superposed over the plate 23 is a plate 24 of insulating material, such as plastic. A handle 25 is attached above the insulating plate 24.

20 The sole plate 20 is preferably a single casting, with a heating element 28 cast integral therein. The heating element is generally U-shaped, with its ends projecting out at the back of the sole plate in two terminals 29 and 30. It will be seen that the bottom part 21 of the sole plate has the lower ironing surface which is flat.

25 The sole 21 extends up a predetermined distance in a beveled edge, and then has a flat platform surface 31 that is substantially horizontal. The casting of the sole plate rises from the shelf 31 to form walls of more or less U-shape. Toward the toe of the iron, the first elevation is shown at 32. This rising portion 32 is rounded at its forward end and extends backwardly somewhat in the shape of an arrow head, as shown in Fig. 12. From its rear ends, two prow-like portions rise further at 34 and 35. These portions or walls slope off toward the front at 36 and slope at their sides to merge with the upper surface 31 on the sole 21. They have inner side edges 37 and 38, which extend downwardly in varying amounts to or below the top surface 31.

30 As shown in Fig. 13, in profile, and also in Fig. 14, there are two circular integral buttons 39 and 40 extending upwardly from the top edges of the two walls 34 and 35. These are to receive screws, as will appear.

35 About midway back of the two walls 34 and 35, there is a lowering of the top surfaces at 41 and 42. At the back, the two surfaces are provided with facing inclined cut-away portions 43 and 44. Adjacent their outer rear edges, two small projections 45 and 46 extend upwardly adjacent the walls 34 and 35. These, as will later appear, form stabilizing means for the location of the cover of the iron.

40 The inner surfaces of the two side walls 34 and 35 and the forward lower rising portion 32 pro-

vide, with the bottom, an enclosure extending inwardly from the back end of the sole plate. This enclosure is open at its top. It includes a forward section 49, which receives the thermal element, as will appear. Slightly ahead of the middle part of the iron, this declivity in the sole plate is lowered at 50 to form a deeper declivity that extends substantially to the back edge of the bottom part 21 of the sole plate. It will be seen that the portion 49 has a central declivity 51 therein, that is slightly below the surface 31, and that the rear declivity 50 is substantially below the surface 31. It will also be seen that the heating element 28 extends around the sole plate largely within the wall parts 32, 34 and 35.

The sole plate assembly, at its back end, is provided with a terminal supporting bracket 54, screwed at 55 and 56 into openings provided in the edge of the sole plate. This bracket extends upwardly and backwardly at an angle, with a turned-over top edge in its medial parts, substantially as shown at 57 in Figs. 12 and 13. The leads 58 and 59 from a power cable are connected to this bracket 54 at electrical terminals 60 and 61. Fig. 15 shows the terminal 61 as comprising two telescoping insulating bushings 62 and 63 that interfit through a suitable opening in the bracket 54. A screw part 64 fits through the bushings 62 and 63 and, at its outer end, receives nuts 65 and 66 that hold the interior connecting line. The exterior connection 59 is made through a screw 67 that is threaded into the screw 64. The head of this screw faces backward and downward. The other terminal 60 may be identically constructed.

The wall 35, adjacent its forward end opposite the cut-away part 49, is provided with an arcuate notch 69 for a purpose that will appear.

The declivity 51 in the bottom of the cut-away part 49 is adapted to receive a bimetal strip 70, screwed down at 71.

The cut-away parts 49 and 50 between the walls 34 and 35 are designed to receive a thermal switch. This switch is built generally upon a bracket 75, shown in plan view in Fig. 7. It bridges across the iron between the two circular buttons 39 and 40 on the top surfaces of the two walls 34 and 35. Two screws 76 and 77 extend into the two buttons 39 and 40, to secure the bracket 75 in place.

Midway along its rear edge, the bracket has a T-shaped projection 78, which has downturned side flanges 79 and 80. These side flanges form pivot pin receiving ears holding a pivot pin 81. This pivot pin also receives upstanding ears 82 and 83 on a lever or arm 84, which is thereby supported for rocking movement. A hairpin spring 85 is riveted to the bracket 75 at 86 and extends downwardly to engage a sloping end part 87 on the lever 84, as shown in Fig. 9. The spring pivots the lever 84 clockwise about the pivot 81 in Fig. 9.

At its outer end, the lever 84 supports two switch contact blades 90 and 91, secured by rivets 92, and duly insulated one from another by an insulating bushing 93 and layers of insulation 94, 95 and 96. A retaining plate 97 may be applied over the top of the insulation to form a holding washer for the head of the rivets.

The blade 90 is a spring blade extending forwardly beyond the end of the lever 84 and provided with an insulating shoe 98 projecting downwardly from its outer end. This shoe is adapted to abut the free end of the bimetal strip 70.

The blade 90 also carries a relatively movable switch contact 99 that is adapted to engage with

a related relatively fixed contact 100 disposed on the outer end of the relatively rigid blade 91. The blade 91 extends rearwardly and has a terminal end 101 thereon. The other blade 90 has a lateral terminal projection 102.

The lever 84, adjacent its outer end, is provided with a lateral projection 105 extending upwardly and over at its upper end. It is disposed to come beneath a thermostat adjustment cam. The thermostat adjustment includes a sleeve 110 threaded into a split extension 111 on the bracket 75. The sleeve is provided with a hexagon head so that it may be adjustably positioned in the bracket, whereby the thermostat may be calibrated. The sleeve 110 receives an adjusting shaft 113, which has a collar 114 thereon limiting the downward movement of the shaft 113 into the sleeve. A retaining ring 115 is located in a groove on the shaft 113 below the sleeve 110 to limit upward movement. At its bottom end, the shaft 113 supports a cam 116 that is in position to engage the projection 105 on the blade 84. The spring 85 causes the blade 84 to pivot in such wise as to maintain the projection 105 against the cam 116.

The shaft 113 extends upwardly from the base plate and has an adjusting wheel 117 at its upper end. Below the sleeve 110, the shaft has a limiting pin 119 that is engageable against the opposite sides of a depending stop 120 which is an integral part of the bracket 75. This pin is given freedom to move, by the notch 69 in the wall 35.

The wheel 117 is formed in conical shape, with a series of radial fins extending over the upper surface, as shown. The fins are good heat dissipators, and, as a result, the adjustment of the wheel by contact of an operator's thumb is not endangered by excess heat at the point of contact. Also, the area between the fins is not normally touched by the hand, and affords a place for imprinted legends that are not rubbed off in use.

It will be seen that the rotation of the handle 117 turns the cam 116, and thereby presets the positions of the two switch blades 90 and 91 relative to the end of the bimetal 70.

The terminal 102 of the switch blade 90 is connected to a wire 125 suitably insulated, preferably by insulating beads, as shown, for example, in Fig. 7, and extending in the cut-away portion 50 back to the rear part thereof where it is electrically joined (Fig. 12) to a jumper 126 that is connected to the terminal 29 of the heating element. The terminal 101 on the blade 91 is likewise connected with a wire 127 that is similarly insulated and that similarly extends backwardly in the depression 50 to be connected with the terminal 60. The other end of the heating element is connected by a wire 128 with the terminal 61.

When the foregoing parts are duly positioned, but without the adjusting wheel 117, the cover plate or shroud 22 of the iron may be disposed over the sole plate. This cover has its edges engaging over the horizontal shelf 31 at the lower part of the sole plate. Preferably it overhangs the rear of the sole plate. It has an opening 130 in its top surface, through which the shaft 113 of the thermostatic adjustment means may project. It also has a keyhole slot 131 at its forward end. As shown in Fig. 2, the material below the opening 131 projects down to form locking cams 132.

At its middle part, the cover has two depressions 133 in its upper surface to receive screws 134, by means of which the cover may be united

to the sole plate. The walls 34 and 35 are duly drilled to receive these screws. At its rear end, the cover has openings to receive handle fixing screws, as will appear. The bottom opening of the overhang is enclosed by a plate 136, held in place by a screw 137 that extends into a post 138 that is secured to a depressed tongue on the top of the cover 22. The cover is also provided with an opening through its top for the passage of the connecting leads.

An insulating spacer, in the form of a skeletonized plate 23, is located over the top of the cover 22. This insulating plate has downturned edges, as shown at 140, for example, in Fig. 8, that rest upon the top of the cover 22. It may have a plurality of openings 141, 142, 143, and the like, in its top surface. Some of these openings may be used to give passage to upwardly projecting parts, or to give access to parts below them. This insulating spacer 23 extends out almost to the back of the projecting part of the cover 22. The side edges are preferably cut away in wide notches 145 at intervals therealong, to provide free passage of air from one side to the other of the iron beneath the plate 23. The forward notches 145 also afford access to the hexagon head on the sleeve 110 of the thermostat which stands above the top of the casing. A narrow wrench may be inserted through the slot for calibration of the thermostat when the iron is assembled.

This plate 23 may be laid over the top of the cover 22. Above it is disposed the plate 24, which is preferably of some heat insulating material, such as a thermosetting plastic.

The plate 24 extends upwardly at its forward end in substantially a continuation of the prow line of the iron. It has a front horizontal surface 148 that is cut away at 149 to receive the thermostat adjusting wheel 117. An opening 150 through this forward portion of the plate 24 provides passage for the upwardly projecting shaft 113 of the thermostat. It is desirable to have the adjusting wheel 117 located a little to one side of the center of these parts, as shown more particularly in Fig. 1.

The plate 24 extends backwardly to the rear of the plate 23 and laterally to the sides thereof, so as to provide insulation over the entire upper surface of the iron. The plate has a hole 152 down through its forward end, for a purpose that will appear. It also has a hole 153 at the rear for a purpose to appear. About a third of the way back of the toe end of the iron, the insulating plate 24 has a projection 155 extending from its bottom surface and shaped to the same shape as the opening 142 in the lower plate 23. Thus, when the upper plate 24 is in place, this projection will hold these two parts fixed against twisting relative to each other. Also the projection 155 has four recesses 157 engageable over four upturned prongs 158 on the cover 22, so that the plates 23 and 24 are held properly against twisting on the cover.

Preferably, too, the plate 24 is cut away on its lower edge, so that it bears directly on the plate 23 only at its toe end and beneath the rear of the handle. This gives an air slot 156 extending across a large part of the extent of the insulating plate 24 from side to side of the iron.

The handle itself may be made of molded material. It has a forward post 160, preferably with a forward edge that aligns with the prow of the iron to give a smooth appearance. It has a rear

post 161 that rests upon the top of the rear part of the plate 24.

The toe of the handle receives a locking rod 162 that is most desirably molded into the handle itself. The shape shown in Fig. 6 provides great security, both against being pulled out and against its being twisted within the handle. The lower end of this rod carries a cross pin 163. When the handle is twisted about 130° from the position shown, the rod 162 will pass through the openings in the several parts, and finally through the keyhole slot 131 in the top of the casing 22. It then is located below the lower edge of the cams 132, and, when the handle is twisted back to the position shown, the cross pin 163 locks tightly beneath the cam member, holding the handle, casing, and intermediate parts securely together.

The rear end of the handle is hollowed out at 168 (Figs. 16 and 17). This provides a receptacle for the electric wires to the iron, and an air space for reduced heat conductivity. An outlet opening 169 through the wall of the handle provides an outlet for the wires, which at this point may be surrounded by the usual protecting spring 170 attached within the outlet opening 169 and securable outside the handle by a nut.

Two metal inserts 171 and 172 are molded into the bottom of the rear post 161 of the handle. Each of these is tapped so as to form a screw-receiving bushing. When the handle is engaged with the casing at its front, and aligned as shown, a pair of screws 173 may be passed in from the bottom of the casing through the two plates 23 and 24 and into the inserts 171 and 172 in the bottom of the handle post. This will provide for final securing together of the casing, plates and handle. The opening 168 in the handle is of sufficient size to permit use of a cable clamp on the wires, or any other means to resist their being pulled out against their securement to the terminals.

The bottom of the post 161 is preferably cut away at 175 and 176 to provide air space beneath the handle post, and thereby reduce the transmission of heat therethrough.

It will be seen that the disassembly of the iron may be made by removal of the plate 136 beneath the overhang of the cover.

The overall assembly of the iron is as follows: The sole plate parts, shown in Figs. 12 to 15, are assembled in the manner shown therein. As stated, the heating element is cast as a part of the sole plate itself. The terminal parts may be added in the obvious manner, and the bimetal strip 70 applied in place. Thereafter, the thermostatic cut-off switch may be applied by the attachment of its bracket 75 to the two buttons 39 and 40 on the top of the sole plate member. The connections 125 and 127 to this switch may readily be made in the foregoing operation. The thermostat may be calibrated by adjustment of the sleeve 110 in the extension 11 of the bracket 75.

Thereafter, the cover 22 is laid over the top of the sole plate, and secured thereto by the screws 134. Then the insulating plate 23 and the plate 24 are, in the order named, disposed on top of the sole plate, following which the thermostat knob 117 is located in place. Thereafter, the connections through the handle may be brought down into the cover plate and screwed onto the terminal connections 60 and 61. It will be seen that the screws for these terminals are accessible through the bottom of the overhang

of the cover 22 when its plate 136 is not in place. Then the handle rod 162 is fitted through the plates and the keyhole slot 131 in the casing, and the handle is turned about 130° from the position shown. The two screws 173 may be inserted from the bottom of the iron through the presently open overhanging part of the cover 22. It will be seen that these two screws 173 are located laterally of the terminals 60 and 61, so that they are accessible. This secures the parts together. Then the plate 136 may be located in position and held there by the screw 137.

When the iron is plugged in, current will be applied through the thermostatic switch to the heating element. When the iron attains a degree of temperature sufficient to raise the bimetal 70 and lift the shoe 98 a predetermined distance, it will break the contacts 99 and 100 and cut off power from the heating element.

The position of the bimetal required to open the two contacts is determined by the adjustment of the wheel 117 and the cam 116, which act through the extension 105 on the lever 84. The lever 84, as already mentioned, is urged to bring its extension 105 against the cam 116 by the spring 85. The lever in Figs. 2 and 9 is shown in its maximum downward position. In Fig. 9, the switch is removed from the iron, but Fig. 2 shows that this cam position opens the contacts and provides an "off" position of the switch. As the cam is rotated from the position shown, the lever 84 will be lifted by the spring 85, the shoe 98 may be lifted from the bimetal 70, and the contacts 99 and 100 will close. The point of closure of the contacts is the lowest heat setting for the iron, as any slight heating and warping of the bimetal 70 will lift the contact 99 away from the contact 100. Further twisting of the cam and lifting of the lever 84 will increase the amount of warping required to break the contacts, and hence increase the iron temperature.

This iron is designed to be cool adjacent the handle. The plate 23 forms a large air space beneath the handle which is open to the free air at the sides of the iron. The plate, being skeletonized, is a poor heat conductor. The plate 24 likewise is open to atmosphere in its space 156. Additionally, the handle itself is provided with the spaces 175 and 176, all of which open to the sides of the iron and permit the circulation of air.

Also, the plate 24 extends from side to side of the iron below the handle, so that a low handle may be used on this iron without the danger of burning the knuckles of the user. The handle construction provides a means for the rapid assembly of these parts.

The operating knob 117 is conveniently accessible to the thumb of the operator. It may be turned readily at any time to change the degree of heat that will be maintained by the iron.

It will also be seen that the elevated parts on the sole plate are all spaced from the shroud 22, so as to provide air spaces between them and the shroud at all points except the bottom edge of the shroud. At the same time, the thermostatic mechanism is substantially enclosed, so as to be influenced by the actual heat of the sole plate. The bimetallic element 70 is almost surrounded by the parts of the sole plate itself, except at its top, and even there is disposed between the wall surrounding it. Also, the switch mechanism is compactly disposed by being located between the walls. It may also be observed that the switch mechanism adjustment does not vary the contact 75

pressure between the contacts 99 and 100 when the cam 116 is turned. This comes about because both switch arms are displaced together by adjustment of the cam. The leads to the switch are completely protected by being located in the space between the two side walls 34 and 35 of the sole plate.

The handle is designed with a convenient thumb rest 180 above the thermostat wheel 117.

If the iron should be dropped, and some part broken, it is not a difficult task to replace such part. For example, if the handle itself is broken, it can be replaced as a single part without involving any of the other parts, such as the plate 24. It may also be remarked that the separation of the handle 25 from the plate 24 provides added coolness of the handle itself because of the relatively poor conductivity between the two parts.

What is claimed is:

1. In an electric iron, a sole plate, a cover thereover, a first plate over the cover providing an air space above the cover, and a hand guard having a second plate above the first plate, said second plate being of heat-insulating material and extending substantially across the top of the iron, a handle member separate from the second plate, the handle member including a hand grip portion and post means for supporting the grip portion above the second plate, and means for securing said parts together, said first plate having downturned edges engageable with the cover, and having a body part supported above the cover by said edges.

2. In an electric iron, a sole plate, a cover thereover, a first plate over the cover providing an air space above the cover, and a hand guard having a second plate above the first plate, said second plate being of heat-insulating material and extending substantially across the top of the iron, a handle member separate from the second plate, and means for securing said parts together, said first plate having downturned edges engageable with the cover, and having a body portion supported above the cover by said edges, said body portion being skeletonized to reduce conduction of heat.

3. In an electric iron, a sole plate, a cover thereover, a first plate disposed above the top of the cover and shaped to provide an air space over the cover, a second plate of insulating material disposed above the first plate, handle means including a front post and a rear post, an attaching member in one post engageable through the plates and cover and securable to the iron by displacement from its position of insertion to a second position, and releasable attachment means engageable through the cover and plates into the other post to hold the parts together with the attaching member in second position.

4. In an electric iron, a sole plate, a cover thereover, a first plate disposed above the top of the cover and shaped to provide an air space over the cover, a second plate of insulating material disposed above the first plate, handle means including a front post and a rear post, an attaching member in one post engageable through the plates and cover and securable to the iron by displacement from its position of insertion to a second position, and releasable attachment means engageable through the cover and plates into the other post to hold the parts together with the attaching member in second position, said cover overhanging the sole plate, and being open at the bottom of the overhang, said attachment means being accessible through said opening.

5. In a sadiron, a sole plate, a first plate, means supporting the first plate over the sole plate, an insulating plate over the top of the first plate, the insulating plate and first plate having interfitting, separable, projection and receptacle elements whereby they may be aligned together, the projection being integrally formed on one of said plates and the receptacle formed on the other, and means for securing the interfitted first and insulating plates and the sole plate together.

6. In a sadiron, a sole plate having a cover thereover, an insulating plate extending over the top of the cover, and a skeletonized spacing plate between the insulating plate and the cover, the skeletonized plate having depending edge portions and a top portion, the top portion being skeletonized to reduce heat conductivity, and means to secure the plates and cover and sole plate together, the skeletonized plate having one cut-away opening in its top portion of predetermined shape, and the insulating plate having an integral projection on its lower surface of complementary shape, to fit down into the said opening and insure alignment of the two plates.

7. In a sadiron, a sole plate having a cover thereover, an insulating plate extending over the top of the cover, and a skeletonized spacing plate between the insulating plate and the cover, the skeletonized plate having depending edge portions and a top portion, the top portion being skeletonized to reduce heat conductivity, and means to secure the plates and cover and sole plate together, the skeletonized plate having one cut-away opening in its top portion of predetermined shape, and the insulating plate having an integral projection on its lower surface of complementary shape, to fit down into the said opening and insure alignment of the two plates, and interfitting projection and receptacle means between the cover and the projection on the insulating plate that passes into said opening of the skeletonized plate, to align the two plates and the cover.

8. In a sadiron, a sole plate, a cover thereover, a first plate substantially coextensive with the top of the cover, having downturned edge portions in contact with the cover, said portions providing limited contact with the cover, the top part of the first plate being skeletonized, an insulating plate substantially coextensive with the first plate, positioned thereabove, and having bottom parts providing limited contact support on the first plate and air space between the two plates, a handle of insulating material having a grip portion and two posts, means connecting one handle post with the cover, through the two plates and attaching the handle, plates, and cover together, means connecting the other handle post, cover and two plates together, one connecting means being removable from the exterior of the said parts, and the other connecting means comprising interlocking parts between the handle post and cover, unlockable by displacement of the other handle post from its connected position relatively to the cover.

9. In a sadiron, a sole plate, a cover thereover, a first plate substantially coextensive with the top of the cover, having downturned edge portions in contact with the cover, said portions providing limited contact with the cover, the top part of the first plate being skeletonized, an insulating plate substantially coextensive with the first plate, positioned thereabove, and hav-

ing bottom parts providing limited contact support on the first plate and air space between the two plates, a handle of insulating material having a grip portion and two posts, means connecting one handle post with the cover, through the two plates and attaching the handle, plates, and cover together, means connecting the other handle post, cover and two plates together, one connecting means being removable from the exterior of the said parts, and the other connecting means comprising pin and slot elements between the cover and the handle post that are releasable when the one connecting means is released and the handle thereat is twisted away from connected position, and which interlock when the handle is twisted into connected position.

10. In a sadiron, a sole plate, a cover thereover, a first plate substantially coextensive with the top of the cover, having downturned edge portions in contact with the cover, said portions providing limited contact with the cover, the top part of the first plate being skeletonized, an insulating plate substantially coextensive with the first plate, positioned thereabove, and having bottom parts providing limited contact support on the first plate and air space between the two plates, a handle of insulating material having a grip portion and two posts, means connecting one handle post with the cover, through the two plates and attaching the handle, plates, and cover together, means connecting the other handle post, cover and two plates together, one connecting means being removable from the exterior of the said parts, the cover overhanging the rear of the sole plate and open at the bottom of the overhang, electrical terminals at the rear of the sole plate, releasable at said open overhang, a wire receiving passage into the handle post at said overhang, and the other handle connecting means being accessible through the open overhang.

11. In a sadiron, a sole plate; a cover for said sole plate having a substantially flat upper surface; a first plate substantially coextensive with said upper surface of the cover and having depending edge portions in contact therewith, the edge portions containing notches at the lower edges thereof to provide limited contact between the cover and the first plate; and a second plate of insulating material disposed above the first plate and having bottom parts providing limited contact support on the first plate and an air space between them, the second plate being substantially coextensive with the first plate.

ERNEST BRAUNER.
